ALBERT D. GROVER, OF NEW YORK, N. Y., ASSIGNOR TO AUTOSALES GUM & CHOCOLATE COMPANY, A CORPORATION OF NEW YORK.

COIN-CONTROLLED VENDING-MACHINE.

1,254,040.

Specification of Letters Patent. Patented Jan. 22, 1918.

Application filed July 27, 1914, Serial No. 853,259. Renewed May 9, 1917. Serial No. 167,581.

To all whom it may concern:

Be it known that I, ALBERT D. GROVER, a citizen of the United States, and a resident of New York, in the County of New York and State of New York, have invented certain new and useful Improvements in Coin-Controlled Vending-Machines, of which the following is a specification.

The object of my invention is to provide 10 a coin-controlled vending machine embodying various features of novelty over the machines heretofore constructed.

Viewed in one of its aspects, my invention 15 comprises a coin-controlled ejecting mechanism associated with two magazines containing the vendable articles and so constructed that it must be operated in alternately opposite directions, so that a package is ejected first from one magazine and 20 then the other, whereby both magazines become empty at approximately the same time.

In the preferred form of my invention, 25 my new form of ejecting mechanism comprises a pair of coin-supports mounted on a common framework and so arranged that they are alternately brought into coin-receiving position. These coin-supports are furthermore provided with means for normally locking the framework against operation. In other words, the ejecting mechanism which is adapted to be operated by 30 hand from the outside of the casing, is normally locked against movement by one or the other of the coin-supports. However, 35 the deposited coin moves the locking coin-support into releasing position and permits operation of the framework in the direction of one of the magazines to cause ejection of a package therefrom. When the framework

40 has reached the end of its movement, it is automatically locked in that position by the other coin-support. When the next coin is deposited, the last-named support is moved into releasing position and the framework 45 is free to be moved in the opposite direction to cause ejection of a package from the other magazine.

Another feature of novelty which characterizes my invention, is the provision of 50 means for intercepting the ejected package in its passage from the magazine to the delivery opening, said intercepting means releasing the package only when the ejecting mechanism completes its movement. The 55 advantage of this intercepting means is that

the ejecting mechanism may be so arranged that a partial movement thereof is sufficient to eject the package from the magazine. However, the purchaser is required to complete the movement of the ejecting mechanism before the ejected package is delivered to the delivery-opening for removal. In the preferred form of construction, I employ but a single intercepting member which is so arranged between the two delivery-chutes 60 leading from the magazines that it extends into that delivery-chute through which the next delivery is to be made. The position of this member is controlled by the ejecting mechanism which engages the intercepting member at the proper time to shift it into releasing position.

Another feature of novelty residing in my invention is a coin-chute mounted midway in the vertical chamber of the casing to divide the same into a pair of upright magazines for containing the vendable articles. By this simple arrangement I do away with the necessity of extra walls or plates to form the magazines, as are found in the prior constructions. I use nothing but the coin-chute 75 itself to form the two magazines. Preferably, this coin-chute is removably mounted in place so that it may be readily taken out of the casing when desired.

The above and other features of novelty and advantages of my invention will become apparent from a detailed description of a preferred embodiment of my invention as shown in the accompanying drawings, in 80 which—

Figure 1, is a front view of a two-compartment vending machine containing my invention, certain of the parts being broken away for the sake of clearness.

Fig. 2, is a longitudinal cross-sectional view approximately on line 2—2 of Fig. 1.

Fig. 3, is a transverse cross-sectional view on line 3—3 of Fig. 2.

Fig. 4, is a cross-sectional view of the 100 frame-work carrying the coin-supports, the section being taken on line 4—4 of Fig. 3; and

Fig. 5, is a fragmentary view in cross-section on line 5—5 of Fig. 1.

The casing of the particular machine shown comprises a rear wall 1, top 2, bottom 3, upper side walls 4, lower side walls 5, upper front plate 6, intermediate front plate 7 and lower front plate 8. The upper front 110

plate 6 forms the door or closure for the magazines and is removable secured in place on the casing. The lower edge of the plate 6 is formed with a flange 9 adapted to enter the recess or channel formed in the projection 10 at the upper edge of the plate 7, as best shown in Fig. 2. The plate 6 is also provided with a peripheral flange 11 which fits over the sides 4 and top 2 of the casing 5 to cover up the joints and prevent the insertion of an instrument in an attempt to remove the cover plate 6. Any suitable means, such as a lock 12 having a bolt 13 may be used for locking the plate 6 in closed position.

The side walls 4, top 2 and cover plate 6, together with the rear wall of the casing, form the chamber 14 for the articles or packages intended to be vended by the machine.

This chamber may be as tall as desired, to give the machine the required capacity. To divide this merchandise chamber into two compartments, I simply use the coin-chute 15, which is supported substantially mid-way of the chamber 14 on a fixed base plate. In the drawings, this base plate is shown as comprising two sections 16 and 17, the section 16 being secured to the rear wall of the casing and the section 17 to the front wall thereof. The coin-chute 15 is at its lower end provided with a pair of oppositely extending wings 18 and 19, which are each provided with a projection 20 adapted to fit into corresponding openings 21 in the plate sections 16 and 17, as best shown in Fig. 2. To sustain the coin-chute in its upright position, any suitable steadyng means may be employed, as for instance, the spring clip 22 secured to the top of the casing and adapted 10 to engage the upper end of the coin-chute. By simply pressing upwardly on the spring clip 22, the coin-chute may be tilted laterally and then lifted out of engagement with the supporting plates 16 and 17. The coin-chute 15 is provided with a forward extension 23 which guides the coin from the entrance slot 24 in the front plate 6 into the coin-chute proper.

It will be observed from Fig. 1 that the plate sections 16 and 17 constitute the supports for the articles or packages in the magazines. In Fig. 1, there are four packages indicated at P¹, P², P³ and P⁴. To prevent the lowermost package from accidentally falling or being jarred out of the magazine, suitable retaining means, such as a spring-pressed gate 25, is arranged to yieldingly engage the package. When the package is forced out of the magazine, as will be described later on, the gate 25 is swung outwardly and permits the package to drop into the delivery-chute.

A shaft 26 is rotatably mounted in the front and rear walls of the casing, and on this shaft is fixed a sleeve 27. The shaft 26 has a pin 28 adapted to engage in the axial slot 29 of the sleeve 27. The front end of the shaft 26 projects out of the casing and has secured thereon a suitable hand-operable member, such as the knob 30. A pin 31 passing through the hub-portion of the knob 30 and the shaft secures these two parts rigidly together. The foregoing connections between the sleeve 27, the shaft 26, and the knob 31, permit these parts to be readily disassembled when desired. To remove the shaft 26 from the casing, it is only necessary to take off the knob 30 by withdrawing the pin 31 and then push the shaft out toward the rear. This sliding movement of the shaft is permitted by the slot and pin connection between the shaft and the sleeve 27.

The sleeve 27 is provided with a pair of shoulders or flanges 32 and 33 to which are secured the disks 34 and 35 by suitable fastening devices, such as bolts or rivets 36. The sleeve 27 and the disks 34 and 35 constitute a rotary framework for supporting the coin-pockets 37 and 38, and the coin-supports 39 and 40. As best shown in Fig. 4, the coin-pockets 37 and 38 are arranged radially between the two disks and spaced approximately 120° apart. Each of the coin-supports is provided with a coin-supporting extension 41 arranged to project through openings 42 in the walls of the associated coin-pocket. Any suitable means may be employed for supporting the coin-pockets rigidly between the plates. In the drawings, I have shown one of the walls of each coin-pocket provided with an extension 43 which enters alined openings in the disks. The coin-support 39 is pivcted on the pin 44, while coin-support 40 is similarly mounted on the pin 45. As shown in Fig. 3, the general outline in plan of the coin-supports is rectangular with the nose or projection 41 extending outwardly from the front or forward edge of this rectangle. These coin-supports are readily bent into shape from a single strip of sheet metal, the ends of which form the projections 41. The side walls of the coin-supports are provided with projections 46. The plate sections 16 and 17 are provided with shoulders 47 and 48, as best shown in Figs. 3 and 4. The relative arrangement of the coin-supports and the shoulders 47 and 48 is such that when the coin-support 39 is in coin-receiving position, as shown in the dotted line position 39* in Fig. 1, the projections 46 are in alinement with the stop shoulders 47 and thus positively lock the framework against rotation toward the left (as viewed in Figs. 1 and 4). Rotation toward the right 125 when the coin-support 39 is in coin-receiving position, is prevented by the stop pin 49 engaging the fixed stop 50 secured to the rear plate 1 of the casing. The pin 49 is carried by the rear disk 34 and is 130

adapted to engage the projection 51 on the stop 50. Similarly, when the other coin-support 40 is in coin-receiving position, that is to say, when the coin-pocket 38 is in the position occupied by coin-pocket 37 in Fig. 4,—the projections 46 on that coin-support will be in alinement with the shoulders 48 of the plate sections 16 and 17 and thereby positively lock the framework 10 against rotation toward the right. In this last-mentioned position of the framework, rotation toward the left is prevented by the stop pin 52 engaging the projection 51 of the fixed stop 50. In other words, the 15 stop pins 49 and 52 limit the rotary motion of the framework in both directions. The position of the stop 52 when the coin pocket 38 is in coin-receiving position, is indicated in dotted lines at 52 in Fig. 4. The coin-support which is in normal position, which is also its locking position, is held in that position by gravity. That is to say, the support, being swingingly mounted, is so weighted or balanced that it normally hangs 20 in a position like that indicated in dotted lines at 39 in Fig. 1. However, when a coin falls upon the supporting extension 41 of the coin-support 39 or 40, the weight of the coin overbalances the support and rocks 25 it into the position in which the coin-support 39 is shown in Fig. 4. In Figs. 2 and 4, the deposited coin is shown at C. It will be observed that when the coin-support is in overbalanced position, the locking projections 46 are beneath the shoulders 47 of 30 the plate sections 16 and 17, and the framework is therefore free for operation toward the left (as viewed in Fig. 4.) The coin-supports coöperate with the associated 35 pockets 37 and 38 to sustain the deposited coin in operative position on the framework which carries the coin into ejecting position, as will be presently explained.

As clearly seen from Figs. 2 and 4, the 40 outer portion of the coin extends beyond the plates 16 and 17. Assuming the parts to be in the position shown in Figs. 1 and 4, when the knob 30 is turned toward the left, the deposited coin is brought into engagement 45 with the lowermost package P^1 in the left-hand magazine and pushes the package out of the magazine into the delivery-chute 53. The package is ejected before the framework has reached the limit of its movement, but, as 50 will be explained later on, it is necessary to complete its movement before the ejected package is delivered to the purchaser. The framework is turned through an angle of about 120° before the stop pin 52 engages 55 the fixed stop 50. When the framework is in its operated position, the coin-pocket 38 will be in vertical alinement with the coin-chute 15, and the projections 46 of the coin-support 40 will be in locking position with 60 respect to the shoulders 48 of the plate sec-

tions 16 and 17. This position of the parts is not shown in the drawings but it will be clearly understood from Fig. 4. Now, when the next coin falls on the coin-support 40, the same is moved into releasing position and 70 the framework is free to carry the deposited coin toward the right against the lowermost package P^2 in the right-hand magazine. The ejected package P^2 falls into the delivery-chute 54 before the framework has reached the limit of its clockwise movement. However, as described in connection with the previous ejecting operation of the framework, the operator must complete the clockwise rotation of the framework in order to 75 secure the ejected package. At the end of its operation, the parts are in the position shown in Fig. 4, except that the coin-support 39 will be in locking position, and will remain in that position until the next coin is deposited. The coin-chute 15 is at its 80 lower end cut away at 55 to accommodate the projecting portion of the supported coin. The space between the plate sections 16 and 17 is, of course, sufficient to allow free movement of the coin. The delivery-chutes 53 and 54 are formed between the side walls 5 of the casing, and the partitions 56 which lead from the ends of the plates 16 and 17 direct the ejected packages into the delivery-openings 57 and 58 at the bottom of the casing. The curved upper ends of the partitions 56 are slotted as indicated at 59 in 85 Figs. 1 and 3, to accommodate the coin in its movement on the framework and allow it to pass into the chamber 60 where it drops by gravity from the framework into the chamber 61 which constitutes the money box. This chamber is closed by hinged plate or 90 door 8 which is locked by any suitable form of locking device. In Fig. 2 I have indicated conventionally any suitable lock 62 having a bolt 63 adapted to engage the lower flange 64 of the front plate 7.

The framework carrying the coin is preferably provided with a centering device so as to insure the coin-receiving positions of the coin-supports 39 and 40. The centering device which I have shown in the drawings consists of a pawl 65 pivoted on the pin 66 110 carried by the front plate 7. A spring 67 coiled about the pin 66 is at one end connected to the pawl 65, while the other end bears against the fixed lug 68 projecting inwardly from the front plate 7. The tendency 115 of this spring is to force the pawl toward the right against the pins 69 and 70 mounted on the framework and projecting forwardly from the disk 35. The pawl 65 is provided with a recess 71 in which the pins 69 and 70 are adapted to engage when the coin-supports are in normal or coin-receiving position. When the coin-support 39 is in coin-receiving position, the pin 69 is engaged by the pawl 65 and the frame- 120

work is thus held against accidental displacement until the operator actually turns the knob after depositing the coin. When the coin-carrier 40 is in coin-receiving position, the pin 70 engages in the recess of the centering pawl 65. The fixed pin or lug 68 extends into the path of movement of the pawl 65 and limits the inward movement thereof when the pins 69 and 70 are out of engagement with the pawl. In order to compel complete movement of the framework in one direction before it can be turned in the reverse direction, I provide a two-way pawl 72 pivoted on the pin 66. A contractile spring 73, connected at one end to a fixed support, such as the lug 74 on the partition 56, and at its other end to the tail 75 of the pawl, normally holds the latter in the position shown in Fig. 1. The front disk 35 is provided on its periphery with a pair of recesses 76 and 77, and between these recesses the periphery of the disk is formed into a series of teeth 78. When the coin-support 39 is in normal position, the free end of the pawl 72 extends into the recess 77. When the framework has been moved sufficiently to the left to cause the pawl 72 to engage one of the teeth 78, the framework is locked against reverse rotation, and it is necessary to move the framework forwardly until the recess 76 comes opposite the pawl 72. When this occurs, the framework has reached the limit of its movement and the coin-support 40 is in coin-receiving position. The same action of the two-way pawl 72 takes place when the framework is turned toward the right.

I have stated above that the ejection of the packages by the coin takes place before the framework has reached the limit of its movement. In a machine which I have constructed substantially in accordance with the drawings, the packages were ejected from the magazines into the corresponding delivery-chutes after the framework had been rotated about 20° , while the total movement of the framework in either direction was about 120° . As we have seen above, the framework must be rotated to the limit of its movement in order to bring the other coin-support into proper position to receive the next coin. Now, if the ejected package were delivered to the operator before the framework had reached the end of its movement, it would very frequently happen that the operator would release the knob as soon as the package appeared in the delivery-opening 57 or 58, and leave the framework in an inoperative position—that is to say, neither one of the coin-supports would be in position to receive the next coin. Consequently, when the next purchaser came along and deposited his coin, he would find that the machine would not deliver, as the

coin simply dropped between the disks 34 and 35 into the money box. Now, in order to insure the proper operation of the machine whenever a coin is deposited, I have provided means which compel the operator to rotate the coin-carrying framework to the limit of its movement before the ejected package is delivered for removal. The means by which I accomplish this consists, broadly speaking, of an intercepting device whose operation is controlled by the ejecting mechanism itself. A simple embodiment of an intercepting device is shown in the drawings in the form of a pair of slideable bars 79 arranged in the chamber 60 below the ejecting mechanism. These bars are supported and guided for horizontal movement by the partitions 56 which are provided with openings through which the ends of the bars extend. The bars are provided with a pair of stop projections 80 and 81 and an intermediate projection 82, as indicated in Fig. 1. When the rotary ejecting framework is in the position shown in Figs. 1 and 4, the pin 83 carried by the disks 34 and 35, bears against the shoulder 84 of the projections 82 of each of the bars 79, and thus holds the left ends of these bars within the delivery chute 53 to intercept the ejected package. The projections 81 on the bars 79 act as centering means to prevent undue movement of the bars toward the left, while the projections 80 on the other end of the bars restrain the same from moving too far to the right. By referring to Fig. 1, it will be seen that when the knob is turned toward the left, that is to say, in a counter-clockwise direction, there is no accompanying movement of the intercepting device until the pin 69 engages the shoulder 85 of the projection 82. This, however, does not occur until the framework has normally reached the limit of its movement. Before this occurs, the lowermost package has been ejected as above explained, and is retained in the delivery-chute 53 by the projecting ends of the intercepting bars. When the pin 69 is in contact with the projection 82, further rotation of the framework shifts the bars 79 toward the right, withdrawing the left ends of these bars from the delivery-chute 53 and at the same time projecting the other ends into intercepting position in the right-hand delivery-chute 54. As the left ends of the bars 79 are withdrawn from the delivery-chute 53, the ejected package falls into the delivery-openings 57 for removal by the operator. In order to effect a more ready removal of the package, I provide a pin or rod 86 in the delivery opening for supporting the rear end of the package and thus causing the forward end to project out of the casing, so that it may be grasped by the fingers and withdrawn. Fig. 2, indi-

ates at 87 how the ejected package is sus-
tained in a forwardly tilted position by the
rod 88.

I believe that I am the first to have pro-
duced a coin-controlled delivery mechanism
for vending machines in which the ejected
package, after leaving the magazine, is in-
tercepted or retained in a position beyond
reach of the purchaser, and is released from
that position only when the delivery me-
chanism has completed its full movement. This
broad combination of a coin-controlled
ejecting mechanism and an intercepting or
retaining device controlled thereby, may be
embodied in different ways.

While I have herein described and shown
in detail a specific construction embodying
the various features of novelty which char-
acterize my invention, I would have it
clearly understood that my invention is not
limited to the mechanical details herein set
forth by way of illustration only, as it is
obvious that in the broad aspect of my in-
vention, as set forth in the appended claims,
the various features may be mechanically
carried out in other ways and forms than
above described.

Having thus described my invention what
I claim as new and desire to secure by Let-
ters Patent of the United States, is:

1. In a coin-controlled vending machine,
a casing provided with a pair of upright
magazines, hand-operable mechanism ar-
ranged below said magazine to carry the
deposited coin into ejecting engagement
with the lowermost articles in said maga-
zines, and means for compelling operation
of said mechanism alternately in opposite
directions to deliver the articles alternately
from said magazines, said coin-carrying
mechanism being in coin-receiving position
at the end of each operative movement.

2. In a coin-controlled vending machine,
a casing provided with a pair of upright
magazines, rotatable mechanism mounted
below said magazines to carry the deposited
coin into ejecting engagement with the low-
ermost articles in said magazines, a rota-
table shaft mounted between the front and
rear walls of said casing for supporting said
mechanism, a hand-operable member ar-
ranged at the front wall of said casing and
connected with said shaft, and means for
compelling operation of said mechanism
alternately in opposite directions to deliver
the articles alternately from said maga-
zines, said coin-carrying mechanism being
in coin receiving position at the end of each
operative movement.

3. In a coin-controlled vending machine,
a casing provided with a pair of upright
magazines, a rotatable framework mounted
below said magazine, a pair of independent
and oppositely arranged coin-supports car-

ried by said framework for supporting the
deposited coin in operative position on said
framework, said supports being so spaced
that they are alternately brought into posi-
tion to receive the deposited coin, hand-
operable means for rotating said framework
to carry the supported coin into ejecting en-
gagement with the articles in said magazine,
and means for positively locking said frame-
work in actuated position and compelling
operation thereof in alternately opposite di-
rections.

4. In a coin-controlled vending machine,
a casing provided with a magazine, a mov-
able framework provided with mechanism
for receiving the deposited coin and sup-
porting the same in operative position, hand-
operable means for actuating said frame-
work to carry the deposited coin into eject-
ing engagement with the articles in said
magazine, and means connected with said
coin-supporting mechanism for normally
locking said framework against movement,
said locking means being moved into in-
operative position by the weight of the de-
posited coin.

5. In a coin-controlled vending machine,
a casing provided with a magazine, a mov-
able framework provided with a coin-receiv-
ing pocket and a swinging member having
a portion extending into said pocket, where-
by said pocket and said member co-operate
to sustain the deposited coin in operative
position on said framework, hand-operable
means for actuating said framework to carry
the sustained coin into ejecting engagement
with the articles in said magazine, a fixed
stop, and an extension on said member
adapted normally to engage said stop and
thereby lock said framework against opera-
tion, said extension being automatically
moved into inoperative or unlocking posi-
tion when said member swings under the
weight of the deposited coin.

6. In a coin-controlled vending machine,
a coin-chute for guiding the deposited coin
into operative position, a rotatable frame-
work comprising a pair of spaced disks, a
coin-receiving pocket arranged between said
disks and normally in alignment with said
coin-chute, a member pivoted between said
disks and having a portion extending into
said pocket to support the coin in operative
position on said framework, and means on
said member for normally locking said
framework against operation, said locking
means being automatically moved into in-
operative or unlocking position when said
member swings under the weight of the de-
posited coin.

7. In a coin-controlled machine, a hand-
operable framework provided with a pair
of independently movable coin-controlled
locking members arranged to be brought

- alternately into position to lock said framework against movement in a direction opposite to the previous movement, and stop means to limit the forward movement of 5 said framework, whereby said locking members and said stop means coöperate to lock said framework in actuated position to compel operation of said framework in alternately opposite directions.
- 10 8. In a coin-controlled machine, a coin-chute, a rotatable framework provided with a pair of coin-supports for sustaining the deposited coin in operative position on said framework, and means for compelling operation of said framework in alternately opposite directions, whereby said coin-supports are alternately brought into alinement with said chute.
9. In a coin-controlled machine, a coin-chute, a rotatable framework provided with a pair of swinging coin-supports adapted to tilt under the weight of the coin and to support the same in operative position on said framework, said framework being rotatable in opposite directions and said coin-supports being arranged to be brought alternately into coin-receiving position, and means connected with each of said coin-supports for normally locking said framework 25 against operation, said locking means being automatically moved into inoperative or unlocking position when the corresponding coin-support is tilted by the coin.
10. In a coin-controlled machine, a rotatable framework, a pair of independent locking members mounted on said framework and so arranged that one or the other of said members is normally in position to lock said framework against operation, said 30 members being adapted to be moved into releasing position by the deposited coin, and means coöoperating with said locking members to compel operation of said framework in alternately opposite directions.
- 45 11. In a coin-controlled machine, a movable framework provided with mechanism for receiving the deposited coin and supporting the same in operative position, means connected with said mechanism for normally locking said framework against operation, said locking means being moved into inoperative or releasing position by the weight of the coin and means coöoperating with said first-mentioned locking means 50 for compelling operation of said framework in alternately opposite directions, said mechanism being in coin-receiving position at the end of each operative movement of said framework.
- 60 12. In a coin-controlled vending machine, a casing having a vertical chamber, an upright coin-chute removably mounted in said chamber substantially midway thereof to divide said chamber into two vertical compartments or magazines for containing the 65 vendable articles, and manually operable ejecting mechanism mounted below said coin-chute to receive the deposited coin therefrom and effect ejection of the articles through the medium of the coin. 70
13. In a coin-controlled vending machine, a casing having a vertical chamber, an upright coin-chute removably mounted in said chamber substantially midway thereof to divide said chamber into two vertical compartments or magazines for containing the vendable articles, manually operable ejecting mechanism mounted below said coin-chute to receive the deposited coin therefrom and effect ejection of the articles 75 through the medium of the coin, and means for compelling operation of said mechanism in alternately opposite directions. 80
14. In a coin-controlled vending machine, a casing having a vertical chamber, a base-plate secured at the lower end of said chamber, a coin-chute having means on its lower end for removably engaging said plate at a point substantially midway of said chamber to divide the same into two vertical compartments or magazines for containing the vendable articles, said coin-chute being supported on said base-plate, means for sustaining said coin-chute in fixed position on said base-plate, and manually 90 operable ejecting mechanism mounted below said coin-chute to receive the deposited coin from said chute and effect ejection of the articles through the medium of the coin. 95
15. In a coin-controlled machine, a fixed 100 plate, a coin-chute on said plate, hand-operable mechanism adapted to receive the coin from said chute and carry the same into operative position, and means on said mechanism adapted normally to engage said plate and lock said mechanism against operation, said locking means being moved into releasing position by the deposited coin. 105
16. In a coin-controlled machine, a fixed 110 plate provided with suitably spaced stop shoulders, a coin-chute arranged over said plate between said stop shoulders, a hand-operable framework carrying a pair of independent locking members adapted to be moved into releasing position by the deposited coin, said members being so arranged on said framework that they alternately engage said stop shoulders, and means coöoperating with said locking members to lock said framework in operated 115 position and compel operation thereof in alternately opposite directions. 120
17. In a coin-controlled vending machine, a casing provided with a magazine and a delivery opening, a delivery-chute leading 125 from said magazine to said delivery-opening, hand-operable mechanism for ejecting the articles from said magazine through the medium of the deposited coin, an adjustable shelf normally extending into said delivery. 130

chute to intercept the ejected article and prevent its delivery to said opening, and connections between said mechanism and said shelf for positively actuating said shelf 5 into releasing position after the article has been delivered on said shelf.

18. In a coin-controlled vending machine, a casing provided with a magazine and a delivery opening, a delivery-chute leading 10 from said magazine to said delivery-opening, hand-operable mechanism for ejecting the articles from said magazine through the medium of the deposited coin, an adjustable device for normally intercepting the ejected 15 article in its passage through said delivery-chute, and means operable only after said mechanism has moved a predetermined amount for controlling the position of said device by said ejecting mechanism to release 20 the intercepted article and permit its travel to said delivery-opening.

19. In a coin-controlled vending machine, a casing provided with a magazine and a delivery opening, a delivery-chute leading 25 from said magazine to said delivery opening, rotary mechanism for ejecting the articles from said magazine through the medium of the deposited coin, a slidable member for normally intercepting the ejected 30 article in its passage through said delivery-chute, and means whereby said mechanism after ejecting the article from said magazine causes operation of said member to release the intercepted article and permit its 35 travel to said delivery opening.

20. In a coin-controlled vending machine, a casing provided with a pair of upright magazines and a pair of delivery-openings, a delivery-chute leading from each magazine 40 to the corresponding delivery-opening, hand-operable rotary mechanism arranged below said magazines between said delivery chutes to cause ejection of the articles through the medium of the deposited coin, and means for compelling rotation of said 45 mechanism alternately in opposite directions.

21. In a coin-controlled vending machine, a casing provided with a pair of upright 50 magazines and a pair of delivery-openings, a delivery-chute leading from each magazine to the corresponding delivery-opening, hand-operable rotary mechanism arranged below said magazines between said delivery 55 chutes to cause ejection of the articles through the medium of the deposited coin, means for compelling rotation of said mechanism alternately in opposite directions, and a coin-receptacle arranged below said ejecting 60 mechanism between said delivery-openings for receiving the coins from said mechanism.

22. In a coin-controlled vending machine, a casing provided with a pair of upright 65 magazines and a pair of delivery-openings,

a delivery-chute leading from each magazine to the corresponding delivery-opening, hand-operable mechanism to cause ejection of the articles through the medium of the deposited coin, means for controlling operation of said mechanism alternately in opposite directions, an adjustable device for normally intercepting the ejected article in its passage through the associated delivery chute, and means for controlling the position of said device by said ejecting mechanism to release the intercepted article and permit its passage to the delivery-opening.

23. In a coin-controlled vending machine, a casing provided with a pair of upright 75 magazines and a pair of delivery-openings, a delivery-chute leading from each magazine to the corresponding delivery-opening, hand-operable mechanism to cause ejection of the articles through the medium of the deposited coin, means for controlling operation of said mechanism alternately in opposite directions, a slideable bar common to both delivery-chutes for normally intercepting the ejected article in its passage through 80 the associated delivery-chute, and means for controlling the position of said bar by said ejecting mechanism to release the intercepted article and permit its passage to the delivery-opening.

24. In a coin-controlled vending machine, a casing provided with a pair of upright magazines and a pair of delivery-openings, a delivery-chute leading from each magazine to the corresponding delivery-opening, hand-operable mechanism arranged below 95 said magazines between said delivery-chutes to cause ejection of the articles through the medium of the deposited coin, means for controlling operation of said mechanism alternately in opposite directions, a slideable bar common to both of said delivery-chutes and arranged below said mechanism for normally intercepting the ejected article in its passage through the associated delivery 100 chute, and means for controlling the position of said bar by said ejecting mechanism to release the ejected article.

25. In a coin-controlled vending machine, a casing provided with a pair of upright 105 magazines, hand-operable mechanism adapted to carry the deposited coin into position to cause ejection of the articles from said magazines, and means for compelling operation of said mechanism alternately in opposite 115 directions.

26. In a coin-controlled vending machine, a casing provided with a pair of upright magazines, rotary mechanism adapted to carry the deposited coin into position to 120 cause ejection of the articles from said magazines, hand-operable means on the outside of said casing for rotating said mechanism, and means for compelling rotation of said mechanism alternately in opposite direc-

tions, whereby said magazines are emptied at substantially the same time.

27. In a coin-controlled vending machine, a casing provided with a pair of upright magazines, hand-operable mechanism provided with a pair of adjustable coin-supports to sustain the deposited coin in position to cause ejection of the articles from said magazines and means for compelling 10 operation of said mechanism alternately in opposite directions, so that said coin-supports are brought alternately into coin-receiving position.

28. In a coin-controlled vending machine, a casing provided with a pair of upright magazines, a pair of coin-supports adapted to carry the deposited coin into ejecting engagement with the packages in said magazines, and means for compelling operation 20 of said coin-supports in alternately opposite directions, whereby one support carries the coin against a package in one magazine and the other support carries the next coin against a package in the other magazine.

29. In a coin-controlled vending machine, a casing provided with a pair of upright magazines, a pair of coin-supports adapted to carry the deposited coin into ejecting engagement with the packages in said magazines, a common framework on which said coin-supports are mounted, means for operating said framework by hand from the outside of said casing, and means for compelling 30 operation of said framework in alternately opposite directions, whereby one support carries the coin against a package in one magazine and the other support carries the next coin against a package in the other magazine.

30. In a coin-controlled vending machine, a casing provided with a magazine and a delivery-chute, coin-controlled mechanism for causing ejection of the packages from 45 said magazines, said mechanism having a predetermined amount of movement from normal to full operated position, means whereby said mechanism causes ejection of the packages during the first part of its predetermined amount of movement, and auto-

matic means whereby the ejected article is held against removal through said delivery-opening until said mechanism has approximately reached the limit of its movement.

31. In a coin-controlled vending machine, a casing provided with a magazine and a delivery-chute, coin-controlled mechanism for causing ejection of the packages from said magazines, said mechanism having a predetermined amount of movement from 60 normal to full operated position, means whereby said mechanism causes ejection of the package during the first part of its predetermined amount of movement, and means actuated by said mechanism whereby the 65 ejected article is held against removal through said delivery-opening until said mechanism has approximately reached the limit of its movement.

32. In a coin-controlled vending machine, a casing provided with a magazine and a delivery opening, a delivery-chute or passage-way leading from said magazine to said delivery opening, hand-operable coin-controlled mechanism for ejecting the articles from said 75 magazine, a movable shelf for receiving the article ejected from said magazine and retaining it in said passage-way, and actuating connections between said shelf and said hand-operable mechanism for positively 80 moving said shelf into position to release the retained package after said mechanism has been operated a predetermined amount.

33. In a coin-controlled vending machine, a casing provided with a magazine, hand-operable coin-controlled mechanism for ejecting the articles from said magazine, and a movable device actuated by said mechanism for receiving and retaining the article ejected from said magazine, said device being positively moved by said mechanism 85 into position to release the retained article only after said mechanism has been operated a predetermined amount.

In witness whereof, I hereunto subscribe 95 my name this 20th day of July, 1914.

ALBERT D. GROVER.

Witnesses:

BEATRICE MIRVIS,
A. A. THOMAS.
